CLAIM

I claim the ornamental design for a pot handle, as shown and described.

DESCRIPTION

FIG. 1 is a front perspective view of a pot handle according to my design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a right side elevational view of FIG. 1; and,

FIG. 7 is a left side elevational view of FIG. 1.
